UNITED STATES PATENT OFFICE

HERBERT W. ORNDOFF, OF NEW ORLEANS, LOUISIANA, ASSIGNOR TO THE E. V. BENJAMIN CO., INC., OF NEW ORLEANS, LOUISIANA, A CORPORATION OF LOUISIANA, TRADING AS MAGINNIS COTTON MILLS

CLAMPING DEVICE FOR WEB-CUTTING MACHINES

Application filed August 24, 1928. Serial No. 301,909.

This invention relates to a clamping device for employment in a web-cutting machine, and is particularly adapted for employment in such machines which utilize a continuous supply of web to the cutting mechanism.

It has been found in practice that for accuracy of cut and for low power demand upon the driving system, it is desirable that the cutting blades should operate successively across the width of the fabric, in order to avoid the jerk in the driving system which might occur if the knife were designed to operate instantaneously for the entire width, and also to gain the advantage of a progressive or scissors-like cut. When this is attempted with a continuous supply of web material to the cutting device, the cutting is apt to be distorted away from the true right angle across the web.

According to the present invention, means are provided for clamping the web on its way to the cutting device, and for its entire width, so that the web is supported during the time for which the knife operates to sever a portion from this web. The clamping device comprises gripping members extending for the width of the machine and normally out of engagement with the web, but adapted to be brought to clamping relationship therewith by means of a cam driven with the knife mechanism so that the clamping occurs at proper timed relationship with respect to the operation of the knife itself. Guide means are provided for delivering the web to the clamping members and for guiding it therefrom to the knife edges proper.

These and other features of the invention are illustrated in the accompanying drawings, which show:

Figure 1 is an end view of a portion of a machine showing the arrangement of the supplying, cutting and clamping devices.

Fig. 2 is a sectional view on a larger scale, taken parallel to Fig. 1, and showing the relationship of the several parts at the moment of clamping and cutting.

Fig. 3 is a similar view of the swinging plate and associated parts, shown in the releasing position for the further delivery of the web prior to a new cutting.

Fig. 4 is a top plan view of one side of the machine.

In these drawings, the machine has a fixed table plate 15 with an upwardly extending standard 15^a thereon providing a bearing for the shaft 20 of the measuring drum 21. The standard 15^a also has a bearing for the cutting shaft 22. Brackets 23 carry a fixed knife 24.

Arms 25 rigidly supported on the standard 15^a are provided with pivots 26 to pivotally support a swinging plate 27 which extends for the full width of the web, and has an angularly bent bottom edge 28. This plate is stiffened at its lower end by an angle iron 29 riveted thereto. At the lower edge of the plate and angle iron are roller brackets 30 to support the pivot pins 31 for the rollers 32. One roller is provided at each side of the machine, beyond the drum and knife, for cam actuation as will be described more closely hereinafter.

The standard 15^a likewise carries an angle bracket 33 having a support 34 thereon for a rubber cushion pad 35 which likewise extends for the width of the web and is located opposite the angle at the lower end of the swinging plate 27 for cooperation therewith to clamp the web, and substantially vertically above the edge of the stationary knife 24. The support 34 also carries a guide plate 36 which removes the web from the measuring drum 21 and guides it down between the swinging plate 27 and the rubber pad 35. After the web has passed between the gripping members 28, 35 when the latter are open, it encounters a second guide plate 37 formed of thin resilient material which delivers it to the edge of the stationary cutting knife 24, from which it passes onto the continuously moving tape 38 passing over the guide roller 39, being carried by the continuous movement of this tape toward the left, in succession as it is fed by the measuring drum 21.

The continuously rotating cutting shaft 22 carries a clamp member 40 to which the revolving knife 41 is fastened in a customary manner by cap screws 42, so that the knife will cooperate with the stationary knife 24 to shear the material with a scissors-like action by reason of the slightly helical shape of the revolving knife.

The cutting shaft 22 further carries at each end a cam member 43 having a hump 44 to cooperate with a swinging roller 32 at the moment of cutting. The arms 25 are provided with spring holders 45 to support one end each of return springs 46 which at their other ends are connected to the swinging plate 27 and cause the same to be normally withdrawn from the rubber pads 35, whereby to permit the web of material to move freely from the measuring drum onto the delivery tape 38. Stop screws 47 are likewise provided in the arm 25 to adjustably limit the clockwise movement of the swinging plate 27 away from the rubber pad 35.

In operation, the sprocket 50 on the cutting shaft and the sprocket 51 on the measuring drum shaft are connected by a chain 52 so that the two members move at a definite speed relationship and with definite angular movements with respect to one another. They are continuously driven from any suitable source of power by a chain drive 53 (Fig. 4) which drives a sprocket 54 on the cutting shaft 22.

As the measuring drum moves, it receives a web of fabric and passes it downward between the gripping devices comprising the angle on the swinging plate 27 and the rubber pad 35, past the stationary knife 24 and onto the delivery tape 38. For the time being, the swinging plate 27 is held away from any gripping action by its return spring 46, and the guides 36 and 37 cooperate to deliver the sheet in regular manner to the delivery tapes 38. It is preferred that the resilient guide plate 37 should be held very close to the edge of the stationary knife 24, and it may be formed of soft brass and permitted to pass beyond the edge of knife 24 a short distance to assure that the material shall not remain hanging or supported on the stationary knife 24. The rotating knife 41 represses the resilient plate 37 without damage to itself or the plate.

During this delivery, the cutting shaft 22 has been rotated with the measuring drum shaft 20, until finally the rotating knife 41 comes into shearing relationship with the stationary knife 24 and shears off the web of material for its entire width. A very short time prior to the beginning of this shearing operation, the rise or hump 44 of the cam 43 has encountered the swinging roller 42 and has forced this roller and therewith the swinging plate 27 to rock counterclockwise about the axis 26 so that the angle of the swinging plate presses the web tightly against the rubber pad 35 for the entire width, and prevents any further downward movement of the web of material past the stationary knife 24. The shearing is accomplished, and immediately following this, the hump 44 passes from opposite the swinging roller 32 and permits the latter and the swinging plate 34 to be returned in a clockwise direction by

the spring 46, so that the web of material is again free to move downward past the stationary knife 24 and onto the delivering table 38. Meanwhile, the delivering tapes have carried along the blank or sheet which has just been cut off.

The clamping operation of the gripping members, as just described, causes a momentary stoppage of the end of the web of material, so that the measuring drum will cause a small accumulation of material in the angle between the swinging plate 27, the guide plate 36 and the drum itself; but such accumulation is easily taken care of in the space.

It may be pointed out that in a machine already constructed the angular displacement about the cutting shaft of the two ends of the helical cutting edge is about five-eighths of an inch for a knife length of fifty inches. In other words, the length of the hump 44 of cam 43 is designed to be slightly greater than five-eighths of an inch in peripheral angular distance.

It is obvious that the invention is not limited to the illustrative example shown and described, but that it may be applied in many ways within the scope of the appended claims.

What I claim as new and desire to secure by Letters Patent is:

1. In a device of the class disclosed, a drum, a cutter to sever a web of material coming from said drum, means to continuously drive said drum and cutter, and means synchronized with the cutter to clamp the web during the time of cutting while permitting the continuous feeding of the web by said drum.

2. In a device of the class described, a feeding drum, a cutter to sever a web of material coming from said drum, means to continuously drive said drum and cutter, fixed guide means to deliver the material from said drum to said cutter, a swinging plate to cooperate with said fixed guide means, means to hold said swinging plate and said fixed guide means, normally separated, and means synchronized with the cutter to move the plate toward said fixed guide whereby to clamp said web during the time of cutting.

3. In a device of the class described, a drum to feed a web of fabric, a guide delivering the web from said drum, a stationary knife mounted with its cutting edge substantially beneath the end of the delivery guide, a rotating knife to cooperate with said stationary knife, driving means to continuously operate said drum and rotating knife, and means synchronized with said rotating knife to clamp the web of fabric during the time of cutting, said clamping occurring substantially vertically above the stationary knife edge.

4. In a device of the class described, a drum to feed a web of fabric, fixed guide means to

- deliver the web from the drum, a stationary knife opposite the end of said guide means, a rotating knife to cooperate with said stationary knife, means to drive said rotating knife and drum continuously, a fixed clamping plate located in said guide, and means synchronized with said rotating knife to clamp the web during the time of cutting, said guide means including a resilient guide member to deliver the fresh cut edge of the web after cutting from said clamp past said stationary knife. 75
5. In a device of the class described, a drum to feed a web of fabric, a frame to support said drum for rotation, a bracket fixed on said frame, a fixed guide on said bracket to deliver the web from said drum, a rubber pad fixed on said bracket, a swinging plate pivoted on said frame, said plate having a rebent lower end presenting an angle for cooperation with said pad to clamp the web of fabric, cutting means to sever the web of fabric located substantially beneath said pad, means to drive said drum and cutting means continuously, and means synchronized with said cutting means to operate said plate to clamp the web during the time of cutting. 80
6. In a device of the class described, a drum to feed a web of fabric, a rotating shaft having a cutter thereon, means to drive said drum and cutter continuously, clamping means to clamp the web of fabric between said drum and cutter, a stationary cutter to cooperate with said rotating cutter, a cam on said shaft, and means cooperating with said cam whereby said cam and means actuate said swinging plate to clamp the fabric during the time of cutting. 85
7. In a device of the class described, a drum to feed a web of fabric, cutting means including rotating and stationary knives, fixed guide means to deliver the web from said drum to said knives, and a moving plate to cooperate with said guide to clamp the fabric between said drum and cutting means, means to drive said drum and rotating knife continuously, and means synchronized with the rotating knife to clamp the web during the time of cutting, said guide and plate forming a collector for the material fed by the drum during such clamping. 90
8. In a device of the class described, a drum to feed a web of fabric, a frame in which said drum is journaled, fixed guide means on said frame to deliver the fabric from the drum, a plate pivoted on said frame and adapted to be swung toward said fixed guide means whereby to clamp the web of fabric, cutting means including rotating and fixed knives, means to drive said drum and rotating knife continuously, means connected to said rotating knife to actuate said plate to clamp the web during the time of cutting, means to normally hold said plate separated 95
- 120
- 125
- 130
- from said fixed guide means, and a stop to limit the movement of said plate away from said fixed guide means.
- In testimony whereof, I affix my signature.
- HERBERT W. ORNDOFF. 70
